UNITED STATES PATENT OFFICE

2,587,915

RAILWAY BRAKE BEAM

Irvin J. Spaeth, Chicago, Ill., assignor to Chicago Railway Equipment Company, Chicago, Ill., a corporation of Illinois

Application May 15, 1946, Serial No. 669,855

16 Claims. (Cl. 188—223.1)

1

The invention relates to railway brake beams of the truss type in which compression and tension members converge near the ends of the beam and are there mounting a brake head and are secured to each other and to the brake head.

In one familiar type of brake beam, commonly referred to as A. A. R. Standard, the head is seated on the end of a channel shaped compression member and the tension rod extends through the head and projects beyond the outer side of the head and a nut is threaded on the end of the tension member and bears against the outer side of the head, thus completing the truss construction. In such a beam, the center line of the tension member extends in a straight line to the nut on the end of the tension member which transfers pressure between the tension and compression members and the axis of the tension member intersects the axis of the compression member outwardly of the beam beyond the center line of brake thrust on the head. At the inner side of the head, the tension member and the compression member web are spaced apart transversely of the beam a distance corresponding to the width of the compression member.

In another familiar type of brake beam, commonly referred to as the Huntoon type, the tension member of the beam meets the web of the channel-shaped compression member adjacent the inner side of the head and then extends parallel to the compression member to the end of the latter which is engaged by a lip on the end of the tension member and a securing device passes through the head and the compression and tension members on the center line of thrust of the head. With this structure, the distance between the compression and tension members transversely of the beam at the inner side of the head is substantially less than in the A. A. R. type previously described, and the ultimate strength of a Huntoon type of beam composed of members of the same cross-sectional area would be substantially less than in the A. A. R. type of beam.

In both types of beams, it is customary to support the beam by a hanger which is seated in a recess provided in the head. In the A. A. R. type of beam, this recess forms an uninterrupted bearing from side to side of the head, but in the Huntoon type of beam, the bearing is apertured for the securing device, thus reducing the area of the hanger bearing.

Objects of the present invention are to increase the strength of the Huntoon type of beam and to

2

increase the bearing area of the hanger recess over similar beams previously constructed.

These and other detail objects, as will appear from the description below, are attained by the structure illustrated in the accompanying drawings, in which:

Figure 1 is a plan view of a Huntoon type of beam embodying the invention, one end of the beam being sectioned.

10 Figure 2 corresponds to the right hand end of Figure 1, but is drawn to an enlarged scale to better illustrate the structure and is taken on the line 2—2 of Figure 4, and

Figures 3, 4 and 5 are detailed sections taken 15 transversely of the beam on the lines 3—3, 4—4 and 5—5, respectively, of Figure 2.

The beam shown in the drawings includes a compression member 1 of channel-shaped cross-section, a tension member 2 of rectangular cross-section, and a strut 3 intermediate the ends of the beam. The end portions of the compression and tension members converge, each end portion of the tension member being received between the compression member flanges 1a and engaging 25 the inner face of the compression member web 1b. A lip 2a on the end of the tension member is seated against the end of the compression member web and flanges.

A brake head 4 is mounted on each end of the beam and includes a body portion 5 and forwardly projecting toes 6 for mounting a brake shoe S. A passage 7 of generally rectangular cross section extends through the head body from side to side of the head. The ends of 30 the tension and compression members extend through this passage. The back wall 8 of the passage engages the web 1b of the compression member and the top and bottom walls 9 of the passage engage the compression member flanges 1a. The front wall 8a of the passage is offset 35 to form a pocket of less height than back wall 8 to receive the tension member, and preferably the pocket walls engage the forward face and the top and bottom faces of the tension member 40 thereby increasing the strength of the beam since it makes the tension and compression members work together more nearly as a unit. The outer side of the brake head, i. e., the side nearest the end of the beam, is recessed at 45 and is provided with a boss 11. The head rear wall 8 is provided with a boss 12 facing in the opposite direction to boss 11. Bosses 11 and 12 have aligned openings and the axis of these openings extends substantially at right angles to the axis of the tension member between the

strut and brake head and diagonally of the center line of thrust of the brake head, as indicated at C, extending in the direction along which the brake forces are applied. A rivet 13 seats on bosses 11 and 12 and passes through the openings in the bosses and through the end portions of the compression and tension members extending through the head passage 7.

Rivet 13 is placed between the end of the beam and the center line of thrust of the head. This construction makes it possible to bring the first contact between the tension and compression members near or outside center line C, thereby spacing the tension member from the compression member web transversely of the beam a greater distance at the inner side of the head than is possible in the usual Huntoon type of beam where the rivet securing the brake head and the compression and tension members is positioned on the center line of thrust of the brake head. The neutral longitudinal axis of the tension member extends more nearly in a straight line to the lip 2a than in similarly constructed beams in which the tension member and compression member neutral longitudinal axes intersect each other at the center line of thrust of the beam head or inwardly of the beam therefrom. Accordingly, the ultimate load carrying capacity of the brake beam is increased and there is little tendency to "straighten out" the bend in the tension member at the head, the section modulus of the beam at its weakest point, approximately on the line M (Figure 2), being double that of the Huntoon type beam in which the tension member contacts the compression member web adjacent the inner side of the head and then extends parallel with the compression member through the head, which arrangement has been customary heretofore to accommodate the securing rivet positioned centrally of the head.

The forward face of the head is provided with the usual central recess 14 for receiving the lower cross-bar of a hanger H by which the beam is suspended from the truck frame. The axes of the recess 14 for the hanger and the recess for securing rivet 13 and the beam receiving passage 7 are in the same plane indicated by the section line 2—2 in Figure 4 which corresponds to the general plane of the beam. The recessing of the outer side of the head as indicated at 10 and positioning of rivet 13 as described makes it possible to continue hanger recess 14 from side to side of the head without an opening for the head mounting rivet as is customary. This gives a bearing for the full length of the lower cross-bar of the hanger which is desirable because it reduces wear on the hanger and hanger recess.

The details of the structure may be varied without departing from the spirit of the invention and the exclusive use of those modifications coming within the scope of the claims is contemplated.

What is claimed is:

1. In a railway truss type brake beam, a compression member and a tension member with their end portions converging, a brake head mounted on and surrounding said end portions transversely of the beam, and a securing device extending in the general plane of the beam through the head and the beam members diagonally of the center line of thrust of the head and positioned wholly between said line and adjacent end of the beam.

2. A railway brake head having a body arranged to surround beam compression and tension members and having elements for mounting a brake shoe, the body having aligned openings for a securing device, the axis of said openings extending diagonally of the center line of thrust of the head and said openings being positioned wholly between said line and the outer side of the head.

3. A railway brake head having a body arranged to surround beam compression and tension members and having elements for mounting a brake shoe, there being a hanger receiving recess extending transversely of the head, and a recess for a securing rivet extending from front to back diagonally of the head with its forward end positioned beyond the end of and spaced from said hanger receiving recess.

4. In a railway truss type brake beam, a compression member of channel-shape cross section, a tension member of rectangular bar cross section, the end portions of said members converging towards each other, a brake head having an aperture for the passage of said members therethrough, said aperture having elements at the inner side of the head engaging the back, top and bottom of said compression member and the front, top and bottom of said tension member and having elements at the outer side of the head engaging the back of the compression member and the front of the tension member, and a securing device extending through the head and said members from front to back and near the outside of the head.

5. In a railway truss type brake beam, a compression member and a tension member with their end portions converging, a brake head mounted on said end portions, and a securing device extending through the head and said members in the general plane of the beam as defined by said members, the head having a hanger receiving recess disposed in said plane, the hanger engaging surface of which is continuous from side to side of the head and the adjacent end of the securing device is positioned substantially between the outer end of said surface and the outer end of the beam tension member.

6. A railway brake head having a through passage to receive the end portions of converging beam compression and tension members, said passage being relatively shallow at one side of the head for surrounding contiguous compression and tension member end portions and relatively deep at the other side of the head for surrounding spaced apart compression and tension member end portions, there being bearings at front and rear of the body for the ends of a device for securing the head to beam compression and tension members, said bearings being positioned wholly between the center line of thrust of the head and the side of the head adjacent the shallow part of said passage, and having a common axis disposed diagonally of the center line of thrust of the head.

7. A railway brake head having a body arranged to surround beam compression and tension members and including webs for engaging the back and front faces of the end portions of the beam and having elements for mounting a brake shoe, the body webs having aligned openings for a securing device, the axis of said openings extending from front to back of the body diagonally of the center line of thrust of the head.

8. A railway brake head having a body arranged to surround beam compression and tension members and having spaced parts for engaging the back and front faces of the beam and for mounting a brake shoe, the body having a central recess extending transversely of the head for receiving a hanger, and the body having an opening extending from front to back of the head through said parts for a member and head securing rivet, the axis of said opening being spaced from said recess.

9. A railway brake head as described in claim 8 in which the body includes a passage from side to side of the head, for receiving beam compression and tension members, and said passage and securing rivet opening and hanger recess lie in the same general plane, and said hanger recess forms a hanger bearing continuous from end to end of said recess.

10. In a railway truss type brake beam, a compression member and a tension member with their end portions converging, a brake head mounted on said end portions, the front of said head having a hanger receiving recess in the general plane of the beam, and an elongated securing device extending through the head and said members parallel to the general plane of the beam as defined by said members and being positioned with its axis spaced from said recess and so arranged as to avoid intersection with said recess.

11. In a railway truss type brake beam, a compression member and a tension member with their end portions converging, a brake head mounted on said end portions, and a securing device extending through the head and beam members diagonally of the center line of thrust of the head.

12. In a railway truss type brake beam, a compression member and a tension member with their end portions converging, a brake head mounted on and surrounding said end portions, and a securing device extending in the general plane of the beam through said head and said members and projecting through the side of the head near the adjacent end of the beam.

13. In a railway truss type brake beam, a compression member and a tension member with their axes converging, a brake head mounted on the end portions of said members, and a securing device extending in the general plane of the beam through the head and beam members substantially at right angles to the axis of the tension member.

14. In a railway truss type brake beam, a channel section compression member and a rectangu-

lar bar section tension member having their end portions converging, a brake head mounted on said end portions, the tension member end portion being received between the compression member flanges and engaging the forward face of the compression member web, the axes of said tension member and said compression member meeting one another outwardly of the line of thrust of the brake head, and a fastening device extending in the general plane of the beam through said brake head and said members substantially at right angles to the axis of the tension member.

15. In a railway truss type brake beam, a compression member and a tension member with their end portions converging, an end member near the end of the beam mounted on and surrounding the corresponding end portions of said tension and compression members transversely of the beam, and a securing device extending in the general plane of the beam through all of said members diagonally of the center line of thrust from the compression and tension members to the end member as the brakes are applied, said securing device being positioned wholly between said line of thrust and the adjacent end of the beam.

16. An end member for a railway truss type brake beam, said member having a body with a passage arranged to receive the end portions of beam compression and tension members and having aligned openings near one of said passages for a securing device, the axis of said openings extending diagonally of the axis of said passage and said openings being positioned wholly between the middle of said passage and said end of said passage.
